Attorney

UNITED STATES PATENT OFFICE

LEWIS J. MEYER, OF TERRERRO, NEW MEXICO

PICTURE FRAME

Application filed February 15, 1930. Serial No. 428,707.

This invention relates to improvements in frames for pictures, business cards and the like, and the primary object of this invention is to provide a frame for supporting a single card having a picture thereon or a single card having a plurality of suitably arranged pictures thereon, the frame according to the present invention preferably being formed of suitably ornate wood, the frame further consisting of a plurality of intersecting strips co-acting to provide as it were, individual frames for each picture carried on the card.

A still further object of the invention is to provide an ornate frame of the character above-mentioned, which is simple in construction, economical, can be readily assembled, and which is admirably adapted for the purpose for which it is designed. Other objects and advantages of the invention will become apparent during a study of the following description, taken in connection with the accompanying drawings, wherein:

Figure 1 is a plan view of my improved frame.

Figure 2 is a horizontal longitudinal sectional view taken therethrough, substantially on the line 2-2 of Figure 1.

Figure 3 is a fragmentary detail view of one corner of the frame.

Figure 4 is a fragmentary detail sectional view for more clearly illustrating the manner of securing the top and bottom and end members to one another as well as the cross members to one another and to the top and bottom and end members of the frame, the section being taken substantially on line 4-4 of Figure 1.

With reference more particularly to the drawings, it will be seen that my improved frame comprises top and bottom rails 5 and 6 respectively, and end rails 7 and 8 respectively, connecting the top and bottom rails 5 and 6 at their ends.

Spaced parallel cross rails 8' extend transversely of the frame between the top and bottom frame members 5 and 6, and said cross members 8' have their ends secured to the top and bottom rails 6. A longitudinal frame member 9 extends transversely of the cross members 8' and at its opposite ends is secured to the end rails 5 and 7 and 8 respectively of the frame.

As clearly suggested in Figure 1, and shown more to advantage in Figure 4, at their intersecting points, the frame rails 7 and 8, 5 and 6, the cross members 8', and the longitudinal member 9, are rabbeted as at 10 to the depth, preferably of one-half their thickness, so that when the entire structure is assembled, the surfaces of the members constituting the structure are flush with each other, both at the front and back of the frame.

As shown to advantage in Figure 2, the top rail 5, bottom rail 6, and end rails 7 and 8 respectively, are each provided with a longitudinally extending flange 11, the flanges of the rails cooperating for confining within the area of the frame circumscribed by the flanges a pane of glass 12, which glass 12 is disposed against the rear faces of the rails, 5, 6 and 7 and 8, and the intersecting frame members 8 and 9, as clearly suggested in Figure 2.

Secured at its marginal edges in any suitable manner, is a backing 13, preferably formed of cardboard to the flanges 11 and providing in conjunction with the pane 12 a pocket 14 adapted to receive therein a card 15, which card 15 on one face thereof may have arranged thereon pictures or display cards, suitably arranged as to be exposed to view through the transparent panel 12, each card or picture being arranged in the area bounded by corresponding parts of the top and bottom and end frame members and the cross members 8 and 9 in a manner clearly apparent.

If desired, the frame members 5, 6, 7 and 8 and the cross members 8' and 9 at their rabbeted portions may be enlarged as clearly suggested in Figure 1, such enlargement adding ornateness to the frame.

As shown to advantage in Figure 3 the top and bottom, and end frame members, at their rabbeted ends may be in addition to being enlarged, shaped in the manner shown in Figures 1 and 3 for purposes of further ornating the frame.

From the foregoing then it will be seen that I have devised an attractive frame wherein two or more pictures may be supported, and while I have herein shown the frame as being capable of supporting six photographs, pictures, or the like, it is of course to be understood that the frame may be of such a size as to be capable of supporting more or less pictures as may be desired.

Even though I have shown the preferred embodiment of my invention, it is to be understood that the same is susceptible to changes in size, shape and arrangement of the several parts as fall within the spirit of the invention as herein described, and the scope of the appended claims.

Having thus described my invention, what I wish to claim as new is:

1. A frame for pictures and the like comprising top, bottom and end members, cross-members, a longitudinal member transversely disposed with respect to said cross members and end members, all of said members respectively being rabbeted adjacent each end thereof and intermediate said ends for interlocking engagement one with the other, said top, bottom and end members respectively provided with a flange longitudinally thereof, a relatively stiff member arranged in the confines of said flanges in spaced relation to the members of the frame, a transparent panel arranged between said frame members and said relatively stiff member, and forming with said relatively stiff member a picture accommodating pocket for the frame.

2. A frame for pictures and the like comprising crossed members, laid the one upon the other and including top, bottom and end members, transverse members, a longitudinal member disposed transversely with respect to said transverse members and end members, all of said members respectively provided with enlarged end and intermediate portions, said members having their respective enlarged portions rabbeted, the rabbeted enlarged portions of the one member having interlocking engagement with the rabbeted enlarged portions of the other at the points of intersection of said members for securing said members together, a relatively stiff member disposed in spaced parallel relation to said frame to one side of the frame, certain of said members provided with longi-

tudinally extending flanges contacting the corresponding marginal edges of said relatively stiff member, said members, said flanges, and said relatively stiff member all co-operating to provide a pocket for the frame, and a transparent medium arranged in said pocket, said relatively stiff member and said transparent medium adapted to receive therebetween a picture or the like.

In testimony whereof I affix my signature.

MR. LEWIS J. MEYER.
